UNITED STATES PATENT OFFICE

93,604

DESIGN FOR A SHEET METAL SNAP FASTENER CAP

Norman A. Dill, Belmont, Mass.

Application February 2, 1934, Serial No. 50,590

Term of patent 14 years

To all whom it may concern:

Be it known that I, NORMAN A. DILL, a citizen of the United States and a resident of Belmont, in the county of Middlesex and State of Massachusetts, have invented a new, original, and ornamental Design for a Sheet Metal Snap Fastener Cap, of which the following description in connection with the accompanying drawing is a specification.

Referring to the drawing which forms a part of my application:—

Figure 1 is a plan view of a sheet metal snap fastener cap showing my new design;

Fig. 2 is an edge view of the cap shown in Figure 1 further illustrating my new design; and
Fig. 3 is a section taken on the line 3—3 of Figure 1.

I claim:

The ornamental design for a sheet metal snap fastener cap as shown.

In testimony whereof, I have signed my name to this specification.

NORMAN A. DILL.
